HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

ADJUSTABLE RUBBING PLATE.

Application filed August 26, 1925. Serial No. 52,501.

My present invention relates to rubbing plates which are used at the ends of meeting rails in windows of the type in which each sash has a projecting plate which extends into an opening formed in the jamb.

I have found that when the window-frames are set in place, the jambs may be slightly bowed inward, and therefore the clearance between the ends of the meeting rails and the center of the jamb face may be quite different after the frame is installed as compared to what it was when the window left the factory. This means either that rubbing plates of various sizes must be provided, or the rubbing plates must be filed down exactly to fill the space between the ends of the meeting rails and the center of the jamb face.

My present invention relates to a rubbing plate of adjustable thickness.

In the accompanying drawings which show an illustrative example of my invention, Fig. 1 is a sectional view through the meeting rails looking at the center of a jamb face showing an adjustable rubbing block in place; Fig. 2 is a similar view without showing the sash meeting rails; Fig. 3 is a section on line 3—3 of Fig. 2, but showing the lower sash slightly raised, and Fig. 4 is a section on line 4—4 of Fig. 2.

In windows of the type referred to, there are provided two slots 10 and 11, between which in this instance there is a T-shaped parting strip 12. At its vertical center the parting strip 12 is provided with two notches 13. The rubbing plate proper is designated by the numeral 14 and is in the form of a U-shaped channel with its ends bent toward the channel opening. This member is preferably made as a stamping, and if desired may be made of brass. In the drawing, the sides of the channel are designated by the numeral 15 and the bent ends by the numeral 16. The rubbing plate 14 has an overall

width exactly equal to the width of the parting strip 12 and its length is the same as the length of the notches 13, so that the sides 15 can enter these notches. Screws 17 pass through the rubbing plate 14 into the parting strip 12. In order to hold the rubbing plate 14 out against the heads of the screws 17, and in order to eliminate any possibility of air passing between the rubbing plate 14 and the parting strip 12, a flat piece of spring

metal 18 is interposed between the parting strip 12 and the rubbing plate 14. This spring metal is cut of a width so it will just fit between the sides 15, and its length is slightly less than the length of the plate 14. It is to be noted that the screws 17 are countersunk into the plate 14 and that the spring plate 18 has slightly elongated openings 19 through which these screws pass.

It is not my intention that this plate shall function in any way as a spring closing device for the window; in fact, this would not be possible with the arrangement shown, as the screws 17 determine both the minimum as well as the maximum effective thickness of the plate. However, with this arrangement, it is possible to form the windows with a substantial clearance between the ends of the meeting rails and the face of parting strip 12 and have the opening thus formed entirely filled when the window is shut; for example, in Fig. 3 it is clear that during most of the movement of the lower sash, there is a substantial clearance between its meeting rail 20 and the parting strip 12. After the windows are installed, the screws 17 are taken up to the point where the meeting rails will make a snug fit against the face of rubbing plate 14, but will operate without further compressing spring 18. It is intended that the rubbing plate shall then remain stationary unless settling of the building or similar cause shall make new adjustment necessary. Repeated painting of the window will only serve to seal any possibility of air leaks back of the rubbing plate, and will not interfere with its operation, since it is not intended to move.

It is to be understood that the foregoing example is given by way of illustration only, and may be modified in many particulars without departing from the spirit of my invention.

What I claim is:

A window-frame and sash construction comprising on each side a parting strip having a substantially continuous face near the centre of the window, sashes having meeting rails of such length as to leave substantial clearances between the ends thereof and said parting strips, a rubbing plate carried by each of said parting strips in such position as to be opposite the ends of the meeting rails when the window is closed, and

having its rear face spaced out from said of each of said plates relative to the parting parting strip and having sides adapted to strips, whereby the position of said plates embrace the sides of the parting strip, a is made adjustable without permitting any 10 compressible member interposed between the substantial amount of air to pass between face of each parting strip and one of said said plates and the face of the parting strip. plates and substantially in contact with said sides, and means for regulating the position
